UNITED STATES PATENT OFFICE.

JAMES B. SHACKEY, OF SAN FRANCISCO, CALIFORNIA.

GRINDING-MILL.

1,245,625.

Specification of Letters Patent.

Patented Nov. 6, 1917.

Application filed March 23, 1914. Serial No. 826,744.

To all whom it may concern:

Be it known that I, JAMES B. SHACKEY, a citizen of the United States, residing at San Francisco, in the county of San Francisco, State of California, have invented a new and useful Grinding-Mill, of which the following is a specification in such full and clear terms as will enable those skilled in the art to construct and use the same.

10 This invention relates to a grinding mill of the Chilian type in which the grinding roller is rigidly restrained so that it will always advance with its axis radial to the driving shaft and at right angles thereto, 15 while free to rise and fall over obstructions or large lumps of ore to be crushed.

Another object of the invention is to produce a mill in which the entire weight of the roller and axle thereof shall be carried by 20 the roller and in which the vertical driving shaft shall only have the weight of the driving head feed box and drive gear to support, thereby reducing the necessity for heavy step or thrust bearings such as are often used where additional weight is sought 25 to be placed on the rollers by the use of devices to restrain the free action of the same.

Another object of the invention is to provide means whereby the enormous vibration 30 due to crushing of the rock will be more or less taken up and not transmitted to the driving shaft, thereby preventing it from becoming quickly crystallized.

A further object of the invention is to 35 provide means whereby the position of the rollers may be easily adjusted radially so that one roller will be caused to travel on the outer portion of the track die, another on an intermediate portion and another on 40 the inner portion, thereby compelling the track die to wear equally on all parts of its upper surface.

A further object of the invention is to 45 provide means whereby the mercury used in the mill at all times will have clear passage-ways for its escape to the cleanup plugs.

An embodiment of the invention is shown 50 in the drawing in which the same reference numeral is applied to the same portion throughout the several views, but I am aware that there are many modifications thereof,

Figure 1 is a vertical sectional view of one form of the complete mill,

Fig. 2 is a side elevation of a portion of 55 the discharge trough around the outside of the screens,

Fig. 3 is a plan view of the complete mill, 60 a portion of the feed pan being broken away for purposes of illustration,

Fig. 4 is a plan view of the central portion 65 of the drive head, portions thereof being broken away to enable the central portion thereof to be better illustrated,

Fig. 5 is a plan view of a portion of a 70 track die and a portion of the seat upon which the track die rests,

Fig. 6 is a side elevation of a portion of 75 the track die and a portion of the seat upon which said track die rests,

Fig. 7 is a vertical sectional view illustrating one roller of a mill of a slightly different type from that shown in the preceding figure in which the entire weight of the drive head and parts assembled thereon is 80 supported by the floating roller axles, the latter being journaled in boxes slidable in guides in said drive head,

Fig. 8 is a view in end elevation of one of 85 the slidable axle boxes and parts adjacent the same, and

Fig. 9 is a plan view of the top of the drive head and one of the axle boxes slidable in the guides thereof.

This mill is installed upon a suitable base 90 1, which base may be of concrete or wood as desired. On an adjoining base 2 there is a bearing 3 for the drive shaft 4, said drive shaft also having a bearing 5 on the base 6 which is bolted to the mill base 1. The base 95 6 has a plain step bearing 7 for the support of the main vertical driving shaft 8.

The mill comprises the grinding pan 9, which pan is cast in one piece and has a bearing 10 at the center connected with the 95 outer portion thereof by means of strengthening ribs 11. This pan has a corrugated track 12 upon which the track die 13 rests, said corrugations extending up the shoulder as indicated at 14 for the purpose of permitting any mercury accumulating between the track die and the inner side of the pan to work down into the corrugations under the track die and out in the outer trough 15 within the pan. The trough 15 extends 100 entirely around the pan on the outside of the track die and is inclined to two discharge passage ways 16 closed by means of plugs

17. Outside of the grinding pan there is a splash trough 18 which leads to the discharge spout 19 for delivering the pulp to a suitable discharge sluice way.
- 5 The outside casing of the mill is made up of a plurality of sections 20 secured together by means of bolts 21, suitable flanges 22 being cast integral with the sides of the pan for that purpose. These sides are flared
- 10 outwardly from the trough 15 and are connected therewith by suitable bolts, not shown, to prevent the sides from being dislodged in the operation of the mill. Each of the side members 20 is provided with
- 15 two lugs 23 and the pan 9 with one lug 24 for each section 20, said lugs being for the purpose of enabling the wedges 25 and 26 to clamp the screen frames 27 in place.

The upper casing of the mill is made in

20 four parts 28 having suitable outturned flanges 29 and secured together by means of bolts 30. This cylindrical casing fits down into the casing formed by the plurality of side pieces 20 and prevents the splash

25 from getting out of the mill except through the screens. In order to keep the splash through the screens from getting on the floor suitable splash plates 32 are provided to contact with the lug 33 for holding said

30 plates in place.

The shaft 8 carries a driving head 40, said head having horizontal flanges 41 which support the feed spouts 42 and the scraper arm 43. The scraper arm 43 is held in position by means of the shim 44 and set screw 45, and at its lower end it is provided with the scraper 46 which extends diagonally across the track die.

It will be observed that while the present

40 mill is shown with three rollers that any number may be used so that while this mill is provided only with six of the vertical cheek-pieces 47 that any other mill would be provided with two cheek-pieces for each of

45 the rollers used. In order to strengthen the cheek-pieces corner webs 48 and 49 are cast integral with the cheek pieces and the horizontal webs 41. Each cheek-piece has a wide groove therein to receive the rollers

50 50, 51, 52 and 53, said rollers being pivotally supported in the drive axle head 54, two at the top and two at the bottom. Each of the rollers is grooved to receive a plurality of balls 55, which balls bear against

55 hardened wear plates 56 and 57 at the sides of the rollers.

It is contemplated that the position of the drive axle heads may be adjusted and this adjustment is effected by the removal

60 or insertion of thinner or thicker shims 58, 59, 60 and 61. The object of this adjustment is to enable the rollers 62, 63 and 64 to be so adjusted as to evenly wear the track die. It will be observed that the roller 62, for example, is in substantially the center

of the track die, while the roller 64 touches the outer edge and the roller 63 touches the inner edge of the track die, note Fig. 3.

Inserted in the guide way of the drive head between each of the shims is a strip of 70 leather or other suitable material as indicated at 65, 66 and 67, the object being to provide a resilient backing for said wearing shims, thus reducing the amount of vibration transmitted from the driving axle to 75 the drive head and the driving shafts. The drive axle 68 extends at right angles to the axle head 54 and where the axle head comes in contact with the sides of the cheek pieces said head is provided with bearing rollers 80 69, said rollers being inserted in pockets in the sides of said axle head.

The driving axle has a suitable flange 70 thereon and at its outer end it is provided with a nut 71 for retaining the roller in 85 place. The bore of the roller is babbitted or lined as indicated at 72 to afford a bearing and the end of said bearing is flanged outwardly as indicated at 73 to afford a bearing for the wear plates 74 between the 90 nut 71 and the end of the bearing after the roller is assembled upon the drive axle 68 and has the nut 71 secured in place. The nut 71 is a split nut and is locked in place after being screwed up by means of the 95 screw 75, whereupon the cover 76 is secured in place by means of the bolts 77, said cover being for the purpose of preventing mud and pulp having access to the axle bearing. In order to prevent water and pulp from 100 running down on to the axle bearing the roller has a deep annular groove 78. In order to prevent grease from getting out of the driving axle and into the pulp being pulverized and thereby interfering with the 105 amalgamation, each roller is provided with a flange 79 and the driving axle head carries a bracket 80 which supports a small trough 81, the upper end of which extends under the flange 79 and the lower end of 110 which discharges on the top of the grinding pan, a flange 82 preventing the grease and oil from getting into the grinding mill, while the pipe 83 permits it to drain to a suitable place of discharge.

115 In order to admit the lubricating fluid to the driving axle, said axle is bored as indicated at 84 and has connecting bores 85 and 86, with the latter of which the pipe 87 connects, said pipe being held in place by means of the bracket 88, which bracket is supported by the driving axle head. The pipe 87 has a union 90 which connects it with a flexible pipe 91, said pipe in turn being connected with a short nipple 92 with which the 120 oil cups 94 are connected.

The oil cups are supported in a central chamber of the feed pan 95, said feed pan being bolted to the top of the driving head as indicated at 96. It will be observed that 130

in order for the flexible pipes to extend from the oil cups to the driving axle that it is necessary for the driving head to have three channels 97 as indicated in Fig. 4, which figure also illustrates the central opening 98

through which the oil feed pipe 99 leading from the feed cup 100 extends, said oil pipe delivering oil into the channel 101 from which it runs behind the key 102 down to the main shaft bearing 103.

It will also be observed that Fig. 4 illustrates the three openings 104 by which the feed pan is secured to the driving head. The feed pan has a projecting throat for each of the feed chutes 42 as indicated at 105. The oil cups are covered over by means of the cover 106 to prevent the pulp from being discharged thereinto and to prevent the pulp from filling up the chamber in which said oil cups are placed.

The shaft 8 is provided with a large bevel gear 107 having its teeth facing downwardly and in mesh with the bevel pinion 108 on the shaft 4. In order to lubricate the bearing 7 a pipe 109 is provided, said pipe having the oil cup 110 connected therewith.

The grinding pan is suitably bolted or otherwise secured to the base upon which it rests.

In the form of the invention shown in Fig. 7 only a portion of the mill is illustrated, the base and driving parts being substantially the same as that shown in the first form of the invention. In this modified form the grinding pan is shown at 120, the track die at 121 and the main drive shaft at 122. This drive shaft carries slideable thereon the driving head 123, said head being suitably keyed to the shaft by means of two keys 124 and 125. The driving head is substantially the same as the driving head shown in the first form of the invention, except that it projects radially slightly more as indicated at 126 and has a cross bar 127 connecting the cheek pieces 128 and 129, said cheek pieces being faced with hardened shims 130 and 131.

Movable in the drive head are the two half boxes 132 and 133, said boxes forming the bearing for the shaft 134 to rotate in. This shaft has flanges 135 and 136 to take up the outward thrust caused by the movement of the wheel around its vertical axis. The two half boxes are suitably connected together by means of bolts 137 and each box at its side has two rollers as indicated at 139 and 140. Each half box has an upwardly projecting arm 142 and a downwardly projecting arm 143 for the purpose of carrying the rollers 144 and 145, of which there is one of each for each of said arms. Each of the rollers has integral therewith a trunnion 147 and 148 which extends through the arms integral with the half journal boxes and said trunnions are bored

to receive a pin shown in dotted lines at 149, Fig. 9, each roller trunnion thereby receiving some support from the adjacent roller trunnion.

The guide way in each cheek piece is provided with resilient bearing strips 150 and 151, said bearing strips having shims 152 and 153 placed thereover to receive the wear due to the movement of the rollers. Each roller is provided with a plurality of balls 75 let into the same as indicated at 153', which balls bear upon a shim 154, each guide way being provided with precisely similar shims and bearing strips.

Supported from the half journal boxes 80 132 and 133 by means of straps 156 and 157 is an inclinel trough 158, said trough being for the purpose of depositing any oil which may run out of the bearing boxes within the ring 159 on the pan 120, thereby enabling 85 said oil to reach the discharge pipe 160 without getting into the ore to be crushed.

The roller 161 is held in place on the shaft 134 by means of the nut 162, said nut having a bolt 163 to lock it in a given adjustment when the roller has been pulled up against the flange 164 on the shaft. The roller is provided with a key way in which the key 165 is slideable and surrounding the roller, which is ordinarily made of cast iron, 95 is a hard iron or steel tire 166.

The drive head is supported by means of a pair of springs 167 over each of the roller axles. These springs bear upon the underside of the transverse bar 127 and at their lower ends they rest upon a transverse bar 168, two bolts 169 preventing said springs from being dislodged and holding the bar 168 in place.

Connected with the half box 132 is an oil pipe 170 which pipe is in turn connected by means of a flexible pipe 171 with the bottom of the feed pan 172 above which the oil cups are installed, precisely the same as in the previous form of the invention. Extending through the bottom of the feed pan is an oil pipe 173 to feed oil to the central opening 174 in the shaft 122 and thereby lead the oil back of the key 125 to the bearing 174'.

It will be noted in this form of the invention that the entire weight of the drive head is carried by the driving axles, thereby affording that much additional weight to effect the crushing of the ore, while at the same time should any one of the rollers wear faster than the other it can move downwardly with respect to the driving head as much as may be necessary, while at the same time if it strikes an unbreakable obstruction 115 such as a hammer it will be free to ride up over the same without unduly disturbing the other parts of the mill. It is also to be noted that if desired the split boxes might be used with the fixed drive head, or that 120 125 130

the form of journal boxes for the rollers shown in Fig. 1 might be used with the form of the invention disclosed in Fig. 7, the precise journaling of the crushing roller being but a minor part of the invention.

Having thus described my invention what I claim as new and desire to secure by Letters Patent of the United States, is as follows, modifications within the scope of 10 the claims being expressly reserved:

1. In a grinding mill, a pan, a track die therein, a shaft extending through the pan substantially at right angles thereto, a spider having a plurality of guideways on 15 said shaft, a roll shaft for each guideway, a roll on said shaft and in contact with the track die, a head connected with the shaft, anti-friction rollers at the side of said head above and below the shaft, shims in the 20 guide ways and in contact with the anti-friction rollers to regulate the position of the rollers with respect to the track die, and friction rollers on axes parallel to the roll shaft against which the guides bear to drive 25 the rollers.

2. In a grinding mill, a pan, a track die therein, a shaft extending therethrough, a spider having a plurality of cheek pieces forming guideways supported by the shaft, 30 a roll shaft for each guideway, a roll on each

shaft, and in contact with the track die, a guide head connected with the shaft, said head having pairs of rollers at the top and bottom for directing its vertical movement, and other rollers movable on axes parallel 35 to the shaft and bearing upon the cheek pieces of the spider guideways for driving the rolls.

3. In a grinding mill, a pan, a track die therein, a shaft extending through the pan, 40 a spider having vertical cheek pieces forming guideways slideable on the shaft, heads slideable vertically in the guideways, a pair of rollers at the top and bottom of said heads and bearing on said guideways, roll 45 shafts extending radially from the heads, rolls on said shafts bearing upon the track die, rollers on axes parallel to the roll shaft axis, and in contact with the cheek pieces of the spider for driving the rolls, and 50 springs for supporting the driving spider from the roll shafts.

In testimony whereof I have hereunto set my hand this 17th day of March, A. D. 1914, in the presence of the two subscribed 55 witnesses.

JAMES B. SHACKEY.
